UNITED STATES PATENT OFFICE.

MARVIN E. HOOD, OSCAR B. ANDERSON, WALTER L. FETTERS, AND JAMES H. McGLINCY,
OF CHESTER, AND JOSEPH E. GAGNON AND WALTER M. KIDDER, OF PHILADELPHIA,
PENNSYLVANIA, ASSIGNEES, BY MESNE ASSIGNMENTS, TO HAMILTON MANUFAC-
TURING COMPANY, OF TWO RIVERS, WISCONSIN, A CORPORATION OF WISCONSIN.

STEEL FURNITURE CONSTRUCTION.

1,244,609.

Specification of Letters Patent. Patented Oct. 30, 1917.

Application filed December 3, 1914. Serial No. 875,370.

To all whom it may concern:

Be it known that we, MARVIN E. HOOD,
OSCAR B. ANDERSON, WALTER L. FETTERS, and
JAMES H. McGLINCY, citizens of the United
5 States, residing at Chester, Delaware
county, and State of Pennsylvania, and
JOSEPH E. GAGNON and WALTER M. KID-
DER, citizens of the United States, residing
at Philadelphia, Philadelphia county, and
10 State of Pennsylvania, have invented and
discovered certain new and useful Improve-
ments in Steel Furniture Constructions, of
which the following is a specification.

Our said invention consists in certain im-
15 provements in the construction and arrange-
ment of parts of steel or metal furniture,
such, for example, as cabinets, type cases,
and other furniture for printing office use,
whereby such furniture is made of a com-
20 paratively inexpensive and light construc-
tion, while at the same time being strong
and rigid to afford substantial support for
the storage compartments, and any other
use for which it may be designed, all as will
25 be hereinafter more fully described and
claimed.

Referring to the accompanying drawings
which are made a part hereof, and on which
similar reference characters indicate simi-
30 lar parts,

Figure 1 is a perspective view of a steel
cabinet structure illustrating our said in-
vention,

Fig. 2 a central vertical section through
35 the same as on the dotted line 2-2 in Fig.
3, the drawers or compartments being
omitted.

Fig. 3 a horizontal section as on the dot-
ted line 3-3 in Fig. 2,
40 Fig. 4 a transverse section on the dotted
line 4-4 in Fig. 2,

Fig. 5 a detail perspective view of the
portion of one end looking at the interior
face thereof,

45 Fig. 6 a detail sectional view through the
central support showing one of the shelf or
drawer support brackets as in process of
assembling,

Fig. 7 a perspective view of the assembled
frame broken out at places to show details 50
of construction,

Fig. 8 a perspective view of the assem-
bled intermediate supporting frame, and

Fig. 9 a detail view showing one of the
feet and its brace more clearly. 55

In said drawings the portions marked A
represent the ends of the cabinet, B the bot-
tom apron, C the top apron, D the interme-
diate support or frame, E the back, F a
supplemental cabinet top, and G the drawers 60
or type cases.

The ends A are formed of sheet steel
pressed into the form as best shown in Fig.
3, the front and rear edges being bent at
right angles with the plane of the end for a 65
distance and then bent inward parallel with
the main outer face of the end, forming
edges 11 with the inturned flanges 12. Chan-
nel braces 13 of sheet steel, in the form of
tongued channels, are secured to the upper 70
and lower edges of said end pieces by spot
welding, or any other desired means. It
will be understood that the particular form
of these channels may be changed as de-
sired, for any particular job, either that 75
shown in the principal views, or that shown
in Fig. 9, being used, as preferred.

The bottom apron B consists of a steel
plate bent to form vertical front and rear
edges 14 with inturned flanges 15 parallel 80
with said bottom or floor. The ends of said
bottom apron fit over the lower channel
braces 13 resting on top of said channels,
and their inturned flanges 15 underneath the
lower flange of said channels, at each end of 85
the cabinet, each end of the apron thus em-
bracing a channel and secured to the flanges
of said channels by screws or bolts 16, or
other suitable means. The only notching of
the parts in the entire construction is at the 90
ends of the top and bottom aprons near
their edges to enable the inturned flanges 15
to slip over the flanges of the channels 13.

The top apron C is similar in formation
to the bottom apron B and its ends embrace 95
the upper channels 13 in a manner the same

as described for the bottom and are secured thereto by screws or bolts 17, or other suitable means.

- 5 The end pieces A with the bottom apron B and top apron C of the form described, secured together as stated, thus form a rigid rectangular frame for the support of the other parts of the cabinet. Notwithstanding the fact that the plates of which these 10 parts are composed are comparatively thin, the inturned wide edges with flanges and braces render said parts not only of a thick and substantial appearance, but constitute an unusually rigid and substantial structure.
- 15 It will be seen that the flanges of said several supporting parts are continuous from end to end and not weakened by notches where strength is required to resist weight or strain. Thus their strength and rigidity 20 is preserved and this constitutes an important feature of the invention.

The intermediate support, or partition, D, consists of two vertical channels 18 and 19 secured by spot welding or other appropriate 25 means to horizontal channels 20 and 21, as will be best seen from an examination of Figs. 2, 6, and 8. This intermediate support is secured in place by screws 22 inserted through perforations in the channels 20 and 30 21 and the bottom B and top C, respectively. The channels 18 and 19 are spaced apart in accordance with the width of the cabinet and the channels 20 and 21 in accordance with the height of the cabinet and together 35 form a rigid rectangular central support to the structure.

The back E consists of a plate of sheet steel with its ends formed with rearwardly bent flanges 23 and with its top and bottom edges 40 formed with inturned horizontal flanges 24. Said vertical flanges 23 fit behind the in-turned flanges 12 of the rear edge of the ends A, while the horizontal flanges 24 are secured by screws 25 to the bottom B and 45 top C, respectively, near their rear edges.

Z-shaped braces 26 are secured to the ends A by spot welding, or other appropriate means, near their rear edges, the rearwardly extending flange being substantially 50 in line with and a short distance from the inwardly turned flange 12 of said end pieces A. The flanges 23 of the back E are adapted 55 to pass through the groove formed between the adjacent edges of said flanges, the back being put in position by first placing one end in position and then sliding endwise until the other end will slide into position, and then inserting said other end, when the screws 25 are put in place and thus 60 add strength and rigidity to the structure.

The supplemental cabinet top F may be formed of a sheet of steel having a downwardly turned flange 27 surrounding its edge

to lend stiffness and rigidity to the top and afford a finished appearance thereto. It is 65 further stiffened and braced by longitudinal braces 28 extending throughout the length thereof from end to end and adapted to fit between the end channels 13 of the structure, extending only to a point adjacent to the 70 inner edges of said channels. The edges 27 of said top F preferably overhang the structure somewhat and are formed with in-turned horizontal flanges 29 adapted to fit against the outer surface of the end pieces 75 A, central support D, and rear edge of top C, as shown.

The supports for the type cases shown, or any other appropriate storage compartments for use in any particular cabinet, consist of vertical plates 30 and 31 having horizontal angle-iron runs 32 secured thereto by spot welding, or other appropriate means. The front vertical plate 30 has an outturned flange 33 on its rear edge and the rear vertical plate 31 has an inwardly turned flange 34 on its rear edge, serving to stiffen said plates for the purpose. The flange 33 of the plate 30 is of a width to bridge across the space represented by the thickness of 85 the edge 11 of the ends A and the flange 34 projects inwardly a distance substantially equal to the width of the runs 32 and serves to stop or limit the inward movement of the type cases, or other storage compartments 90 sliding on said runs.

Each upright plate 30 has an interlocking plate 35 secured to the back thereof by spot welding, or other means, a short distance back from its front edge, as at a point 36. 100 Said plate 35 instead of being a continuous plate extending from top to bottom may consist of several short sections, or hooks, if preferred. Whether in a single plate or in sections it is off-set at the outer edge from 105 the face of plate 30 sufficient to form a groove adapted to receive the inturned flanges of the edges of ends A and of the central support D. The construction and arrangement of these parts is most clearly 110 illustrated in Figs. 5 and 6. In Fig. 6 one of the supports is shown in adjusted position and the other in position just as the support is being assembled, which operation is completed from said position (as shown 115 at the lower side of Fig. 6) by sliding said part over the flange of the upright 18 and swinging the part into position with the plate 31 resting against the face of the flange of the upright 19. When in place it 120 also locks the back securely in place. The parts are secured at their rear edges by screws 36 passing through said parts into perforations in the supports 26 at the ends and the flanges of the upright 19 at the center of the structure. 125

The cases G, of any character desired, or of any ordinary or approved steel construction are slid into place and used as in cabinets of ordinary construction and arrangement.

It will be understood, of course, that other characters of storage compartments may be used and that the supports therefor may be varied in character and distance apart to accommodate the character of storage compartment desired.

In Fig. 9 we illustrate more clearly the manner of supporting the cabinet on the floor. Each of the channels 13 has a foot or 15 "dome of silence" 61 attached to or struck up in its lower flange adapted to serve as a rest and support for the structure. An angle iron brace 62 formed to just fit between the upper and lower flanges of the channels 20 13 is inserted and secured between said flanges to support the lower flange and transmit the thrust upwardly to the complete end structure.

In this structure the ends are reinforced 25 by channels continuous from front to back, and in the entire structure the only notching of the parts is at the ends of the top and bottom aprons near their edges to enable the inturned flanges 15 to slip over the flanges 30 of the channels 13. Thus the parts are rendered very stiff and rigid without adding surplus metal with its consequent weight and expense, and a structure is provided which is capable of resisting great strain 35 notwithstanding the comparative lightness of the material used in its construction.

By this construction, as will be seen, a cabinet is provided wherein all of the parts may be formed rapidly, and with comparatively small expense, from sheet steel and readily assembled without requiring especially trained or unusually skilled artisans for the purpose, while as a whole the cabinet 45 presents an attractive finish and is of a very substantial and durable character.

Having thus fully described our said invention what we claim as new and desire to secure by Letters Patent is:

1. In a cabinet of the character described, 50 the combination of a bottom wall, end walls having channel bars secured thereto, a rear wall, and a top wall each constructed of sheet metal, and said top wall fitting over said channel bars and having upwardly disposed edge portions, a removable cover for the top wall constructed of sheet metal and having inturned edge portions engaging with the edge portions of said top wall, and reinforcing channel bars for the cover fitting 55 within the space provided by said edge portions of the top wall, said reinforced walls 60 constituting a rigid unit structure when assembled, substantially as set forth.

2. In a cabinet of the character described, 65 the combination of a bottom wall constructed of sheet metal and having inturned edge portions, end walls of sheet metal having inturned edge portions, reinforcing channel bars for the end walls extending along the upper edges thereof, a top wall of sheet 70 metal having upturned edge portions, cut-away to fit the channel bars of the end walls, a rear wall of sheet metal having inturned flanges engaging with said top and bottom walls and outwardly turned flanges engaging 75 with said end walls, a partitioning wall comprising upright channel bars, and transversely disposed channel bars secured to said upright channel bars; a removable cover for the top constructed of sheet metal having downwardly turned edge portions engaging with the edge portions of said top wall, and reinforcing channel bars for the cover fitting within the space provided by the edge portions of said top wall, said reinforced walls constituting a rigid unit structure when assembled, substantially as set forth.

3. The combination with a cabinet having 80 a wall thereof constructed of sheet metal and formed with inturned end portions, of plates supporting drawer guides removably fitted to the inturned end portions of said cabinet wall, members mounted on said wall and on one of said plates, respectively spacing said guide supporting plates from said wall, and means securing said plates to said wall, substantially as set forth.

4. The combination with a cabinet having 95 a wall thereof constructed of sheet metal and formed with an inturned flange at one edge thereof, of a pair of vertically disposed plates fitted to said wall, drawer guides mounted on said pair of plates, a locking device carried by one of said pair of plates engaging with the inturned flange portion of the wall, and means securing the other of said pair of plates to said wall, substantially as set forth.

5. The combination with a cabinet having 110 a side wall thereof constructed of sheet metal and formed with inturned flanges at its vertical edges, and a sheet metal rear wall secured to one of said inturned flanges, of a pair of vertically disposed plates fitting 115 against the other flange of the side wall and the rear wall, members spacing said vertically disposed plates from the side wall, drawer guides mounted on said pair of plates, a locking device carried by one of said pair of plates 120 engaging with one flange of the side wall, and means for securing the other of said pair of plates, substantially as set forth.

6. The combination with a cabinet of a 125 partition therefor comprising a pair of ver-

4

tically disposed channel bars, horizontally disposed channel bars secured to said vertical channel bars, two pairs of vertically disposed plates respectively fitting against 5 the opposite sides of said vertical channel bars, drawer guides mounted on each pair of said plates, two adjacent plates of said pairs constructed with flanges adapted to engage and provide a spacing element, locking devices 10 mounted on said flanged plates engaging with one of the vertical channel bars, and means securing the others of said plates to the second channel bar, substantially as set forth.

In witness whereof, we have hereunto set 15 our hands and seals at Chester, Pennsylvania this 24th day of November A. D., nineteen hundred and fourteen.
